CHECKERWORK

Application filed February 20, 1930. Serial No. 429,914.

The present invention relates broadly to the art of checker work for regenerative furnaces, hot blast stoves and the like, and more particularly to an improved construction of checker work and improved checker bricks for use therein.

In the production of checker work for uses of the character referred to, there are certain factors which must be taken into accounting 10 and which to a certain extent oppose each other. For example, it is desirable to provide the maximum amount of heating surface, measured in square feet, and at the same time obtain the maximum amount of free area in 15 the checker work. It will be apparent that if the checker bricks are made larger to afford a greater heating surface, the amount of free area will be correspondingly reduced.

At the present time it is customary to construct checkers in accordance with a number 20 of more or less standard designs. These designs are of such widely different characteristics as to afford from 2.54 square feet of exposed heating surface per cubic foot of checker work to 6.14 square feet of exposed heating 25 surface per cubic foot of checker work. With a typical construction in which the smaller number of square feet of heating surface is provided, there is available .49 square foot of 30 free area per square foot of horizontal checker area, while with the construction affording greater heating surface there is but .29 square foot of free area per square foot of horizontal checker area.

The maximum of free area per square foot 35 of horizontal checker area obtainable with standard structures is .56, this condition being obtained with a brick construction affording 4.03 square feet of exposed heating surface per cubic foot of checker work.

In accordance with the present invention there is provided a construction in which it is possible to obtain 5.1 square feet of exposed heating surface per cubic foot of checker work with .66 square foot of free area 45 per square foot of horizontal checker area. The advantages of such a construction will be readily apparent to those skilled in the art.

In addition to the above, the present construction affords a vertical flue of maximum

dimensions, thereby permitting a free flow of the gases through the checker.

Also in addition to the above, it is desirable to provide a structure in which there is free communication between the different 55 vertical flues thereby affording a more or less free passage diagonally of the entire checker. Such a diagonal flow is freely permitted by a checker constructed in accordance with the present invention. 60

One of the objections to checkers as ordinarily used is occasioned by the tendency of foreign material to accumulate on the checker surfaces. With bricks of the construction herein contemplated, this objection is obviated, inasmuch as the bricks have inclined 65 upper surfaces affording a minimum area on which solid materials can collect.

In the accompanying drawings there are illustrated certain preferred embodiments of 70 my invention.

In the drawings Figure 1 is a perspective view illustrating one type of construction in which the longitudinal and transverse rows are directly superimposed throughout the 75 entire checker area,

Figure 2 is a view similar to Figure 1 illustrating a slightly modified construction in which the longitudinal bricks are directly superimposed, but in which the transverse 80 bricks are staggered in alternate courses,

Figure 3 is a top plan view of a portion of a checker constructed in accordance with the disclosure of Figure 1,

Figure 4 is a vertical sectional view on the 85 line IV—IV of Figure 3,

Figure 5 is a vertical sectional view on the line V—V of Figure 3,

Figure 6 is a view similar to Figure 3 illustrating in plan a checker constructed in accordance with the showing of Figure 2, 90

Figure 7 is a vertical sectional view on the line VII—VII of Figure 6, and

Figure 8 is a vertical sectional view on the line VIII—VIII of Figure 6. 95

It will be understood that the terms "longitudinal" and "transverse" as used throughout the specification and claims are purely relative terms used for purposes of description and not by way of limitation. For purposes 100

of further facilitating a description and understanding of the invention, the bricks forming the so-called transverse courses will be designated as bridge bricks, while the 5 bricks constituting the so-called longitudinal courses will be designated as tie bricks, the respective bricks having slightly different characteristic features.

By reference more particularly to Figure 1 10 of the drawings, it will be apparent that the bridge bricks B each comprises an intermediate body section with a head 2 formed on each end thereof. The intermediate body portion is formed to provide oppositely inclined upper and lower edges 3, the bricks being illustrated as of such construction that they are reversible end for end or edge for edge.

The upper and lower edges 4 of the heads 2 15 preferably provide plane or substantially plane surfaces which are adapted to cooperate either with a foundation on which the bridge bricks are directly placed, or with the tie bricks with which they cooperate. 20 Beyond the plane surfaces 4 the ends both on the upper and lower edges are shaped to provide inclined tie brick engaging surfaces 5. Intermediate the inclined portions 5 are flat or substantially flat end surfaces 6.

The tie bricks T illustrated in Figure 1 are 25 also preferably of such construction that they may be reversed end for end or edge for edge. Each of the tie bricks is preferably shaped to provide an intermediate body portion having oppositely inclined upper and lower edges 7. These edges adjacent the ends of the brick are cut away to provide outwardly projecting shoulders 8 and substantially horizontally disposed shoulders 9, the portion 30 of the ends intermediate the shoulders 9 providing oppositely inclined surfaces 10.

The inclination of the surfaces 10 is preferably such as to exactly coincide with the inclination of the inclined end portions 5 of 35 the bridge bricks B, while the width of the shoulders 9 is substantially equal to the width of the plane supporting edges 4. The length of each of the shoulders 9 is preferably equal to half the width of one of the heads 2. 40 By reason of this construction, it will be apparent that when the bricks are in assembled relation to form a checker, the end surfaces 11 of the tie bricks lie substantially in the plane of the ridge 12 intermediate the inclined upper and lower edges 3 of the bridge bricks, while the flat end faces 6 of the bridge bricks lie substantially in the plane of the ridges 13 between the inclined surfaces 7 of the tie bricks. In this position the shoulders 45 8 prevent endwise movement of the tie bricks, since they form an interlocking engagement with the bridge bricks, movement of the bridge bricks being likewise prevented due to this interlocking engagement. The square shoulder engagement between the tie bricks 50

and the bridge bricks also prevents any tendency of one to tip or roll relative to the other and enables the checker to be built to any desired height.

A checker constructed in the manner described appears in plan substantially as illustrated in Figure 3, in which the tie bricks T constitute the longitudinal courses and the bridge bricks B the transverse courses. 70 From this figure it will be apparent that vertical flues F of maximum cross sectional area extending from the top to the bottom of the checker are afforded.

In Figure 4 there are indicated in shade lines zones 14 which illustrate the free flow 80 space provided from the top to the bottom of the checker in a diagonal direction, the flow space extending above and below the bridge bricks B. By reason of the inclined surfaces 3 in these bricks B, greater freedom of flow 85 in a diagonal direction is permitted than would be possible if square shoulders were utilized. At the same time, the inclined surfaces extend at a pitch such that the coefficient of friction between the same and any foreign material carried by the gases 90 being handled is not sufficient to maintain such foreign material in position on the surfaces. They are thus self-cleaning, whereby the life of the checker is very materially increased. 95 This is true not only for the reason that the accumulation of foreign material and consequent clogging of the checker is prevented, but for the reason that there is not a tendency for local burning out of the checker such as occurs under an accumulation 100 of incandescent particles of foreign material.

In like manner it will be apparent from Figure 5 that a free diagonal flow in the opposite direction is permitted. In this figure there are indicated in suitable shade lines 105 diagonally extending zones 15 passing above and below the respective tie bricks T. These bricks in like manner, due to their inclined upper and lower edges 7, provide a maximum flow zone diagonally of the checker and prevent the accumulation of foreign material on the checker. As before pointed out, it is 110 possible with this type of construction to provide a maximum free area per square foot of horizontal checker area with a maximum area of exposed heating surface per cubic foot of checker work, and a vertical flue of maximum cross sectional area. 115 In this manner the gas handling capacity of the checker is maintained at a maximum while affording a maximum surface through which heat exchange may take place.

In Figures 2, 6, 7 and 8 of the drawings, 120 which are directed toward a slightly modified embodiment of the invention, the same reference characters having, however, a prime affixed thereto are utilized to designate corresponding parts of the structure. 125

The embodiment illustrated in these figures is similar to that already described with the exception that the bridge bricks B', while being of a construction identical with that heretofore described, are so disposed as to be staggered one with respect to the other in alternate courses. The tie bricks T', however, are of slightly different construction in order to accommodate the staggered arrangement of the bridge bricks. This result is obtained by making the upper and lower edges of the tie bricks of slightly different constructional characteristics. As illustrated in this figure, the lower edges of each of the tie bricks are of the same construction as that heretofore described. The upper edges, however, are shaped to provide a depression intermediate the ends, which depression has a length equal to the width of the heads 20 2' so that each recess is adapted to cooperate with the ends of two adjacent bridge bricks. The interlocking engagement afforded between the tie bricks and the bridge bricks is the same as that heretofore described, the 25 principal difference being that the transverse bricks lie in different vertical planes in different horizontal courses. From a consideration of Figures 7 and 8, however, it will be apparent that there is still afforded opportunity for diagonal flow through the checker, the zones 14' and 15' illustrating the direction and quantity of such flow.

With either type of construction it will be apparent that the bridge bricks are in end to end abutting relationship throughout the complete area of the checker and that the same is true as to the tie bricks. This abutting engagement between the ends of adjacent bricks further assists in maintaining the 40 parts in the desired position.

Bricks of the character herein disclosed are capable of being easily manufactured and, due to their reversible characteristics, of being easily installed. When installed in accordance with either of the practices herein illustrated and described, they afford all of the operating advantages and characteristics which have been set forth.

While I have herein illustrated and described certain preferred embodiments of the invention, it will be understood that changes in the construction, arrangement and relative dimensions of the parts may be made without departing either from the spirit of my invention or the scope of my broader claims.

I claim:

1. In a checker work, superimposed courses of bricks arranged in longitudinal and transverse rows, all of said bricks having inclined upper edges, the bricks in one of said rows having enlarged heads with inclined seats cooperating with similarly inclined seats on the bricks in the other of said rows.

2. In a checker work, superimposed courses

of bricks arranged in longitudinal and transverse rows, all of said bricks having inclined upper edges, the bricks in one of said rows having enlarged heads with inclined seats cooperating with similarly inclined seats on the bricks in the other of said rows, said heads also providing substantially plane supporting portions.

3. In a checker work, superimposed courses of bricks arranged in longitudinal and transverse rows, all of the bricks in one of said rows being of increased cross sectional area adjacent the ends of the bricks, and the bricks in the other row being of decreased cross sectional area adjacent the ends of the bricks, said portions of increased and decreased cross sectional area forming an interlocking engagement between the bricks preventing tilting thereof.

4. In a checker work, superimposed courses of bricks arranged in longitudinal and transverse rows, all of said bricks having inclined upper and lower edges, the bricks in one of said rows having enlarged heads with inclined seats cooperating with inclined edges of the bricks in the other of said rows.

5. In a checker work, superimposed courses of bricks arranged in longitudinal and transverse rows, all of said bricks having inclined upper and lower edges, the bricks in one of said rows having enlarged heads with inclined seats cooperating with inclined edges of the bricks in the other of said rows, said heads also providing substantially plane supporting portions.

6. In a checker work, superimposed courses of bricks arranged in longitudinal and transverse rows, all of the bricks in one of said rows being of increased cross sectional area adjacent the ends of the bricks, and the bricks in the other row being of decreased cross sectional area adjacent the ends of the bricks, said portions of increased and decreased cross sectional area forming an interlocking engagement between the bricks preventing tilting thereof, all of the bricks having inclined upper and lower edges.

7. As an article of manufacture, a bridge brick for checkers, comprising a body portion having inclined upper and lower edges and having heads formed on each end thereof, said heads having substantially plane supporting surfaces, and also having inclined seat forming portions, the inclination of said seat forming portions being substantially equal to the inclination of the upper and lower edges.

8. As an article of manufacture, tie bricks for use in checkers comprising body portions having inclined upper and lower edges, said inclined edges being cut away at predetermined portions thereof to provide substantially horizontally and vertically extending shoulders.

9. In a checker, bridge bricks comprising

body portions having heads on each end thereof, said heads having inclined portions formed thereon, and tie bricks having inclined upper and lower edges cooperating with such inclined portions.

10. In a checker, bridge bricks comprising body portions having heads on each end thereof, said heads having inclined portions formed thereon, and tie bricks having inclined upper and lower edges cooperating with such inclined portions, said bridge bricks and tie bricks being shaped to substantially interlock one with the other and provide flat surface engagement effective in both horizontal and vertical planes.

11. In a checkerwork, superimposed courses of bricks arranged in end to end relationship in longitudinal and transverse rows, each of the bricks being formed on its upper and lower surfaces with both inclined and flat contacting supporting surfaces, with the flat surfaces on an upper row resting upon the flat surfaces of a lower row, and the inclined surfaces of the respective rows in vertically and horizontally overlapping engaging and supporting relationship.

12. As an article of manufacture, a refractory brick for checkers comprising a body portion and enlarged end portions, said body portion having opposite tapered portions forming ridges, and said end portions having inclined seat forming surfaces, extending at substantially the same angle as said ridge forming tapered portions.

13. As an article of manufacture, a refractory bridge brick comprising a body portion formed with tapered upper and lower sides to provide upper and lower ridges, and heads, one on each end of the body portion, each head having a plurality of plane surfaces for engaging other bricks in a refractory structure, at least one of said plane surfaces being inclined, said inclined surfaces extending at substantially the same angle as said ridge forming tapered portions.

14. As an article of manufacture, a refractory brick for checkers comprising a body portion and enlarged end portions, said body portion having opposite tapered portions forming ridges, and said end portions having plane supporting surfaces for engaging a horizontal supporting surface with the ridges disposed at the top and bottom of the brick, and having inclined surfaces for engaging similarly inclined surfaces of an adjacent brick, said inclined surfaces extending at substantially the same angle as said ridge forming tapered portions.

In testimony whereof I have hereunto set
my hand.

WILLIAM H. DRAIN, JR.
